SLED WITH SKI ATTACHMENTS

Richard W. Turner, 1786 Tubbs St.,
Thousand Oaks, Calif. 91360

Filed July 14, 1972, Ser. No. 271,734

Term of patent 14 years

Int. Cl. D12—14

U.S. Cl. D12—9

FIG. 1.

FIG. 2.

FIG. 3.

FIG. 4.

FIG. 5.

FIG. 1 is a top view of a sled with ski attachments, showing my new design;

FIG. 2 is a side elevational view thereof;

FIG. 3 is a bottom view thereof;

FIG. 4 is a front view thereof; and

FIG. 5 is a rear view thereof.

The side not shown is a mirror image of the side shown in FIG. 2.

I claim:

The ornamental design for a sled with ski attachments, as shown and described.
